UNITED STATES PATENT OFFICE.

CARL G. HUTH, OF PORT BYRON, NEW YORK.

RAILWAY GATE.

Application filed September 1, 1922. Serial No. 585,712.

To all whom it may concern:

Be it known that I, CARL G. HUTH, citizen of the United States, residing at Port Byron, in the county of Cayuga and State of New York, have invented certain new and useful Improvements in Railway Gates, of which the following is a specification.

My invention relates to railway gates of the kind that are used at level crossings of roads and streets.

At such crossings it is customary to provide a boom erected on each side of the track in such a manner that when the booms are felled down across the street or road they will practically prevent the passing of any vehicle across the railway track.

The object of this invention is to furnish automatic means for lowering the booms upon the approach of a train and to similarly raise the booms when the train has passed the crossing. This lowering and raising of the booms is generally done by hand. This invention is carried out by furnishing a treadle adapted to be operated by the wheels of a passing train and to connect the treadle with one of the booms so that the latter will be felled across the street. Another object of the invention is to furnish a connection between the two booms, so that the one actuated by the car wheels in turn will operate the other boom.

In the accompanying drawings one embodiment of the invention is illustrated, and

Fig. 1 represents a plan view of a railway line having two tracks for trains running in opposite directions and showing the gates in position;

Fig. 2 is a section of a standard for one of the booms, this section being taken parallel to the track along line 2-2 of Fig. 1;

Fig. 3 is a transverse section of Fig. 2 along line 3-3 of said figure;

Fig. 4 is a cross section of the track along line 4-4 of Fig. 1, and

Fig. 5 is a portion of the rail to which an actuating treadle for the device is attached.

In the drawings reference numeral 10 represents one track of a railway with the trains running in direction of arrow X and reference numeral 11 represents another track for trains running in opposite direction as indicated by arrow Y. The inner rail of each track is denoted respectively

by reference numerals 12 and 13 and reference numeral 14 indicates a railway crossing.

On the outer side of track 10 and close to the crossing 14 is situated a standard 15 rigidly secured on a suitable foundation. In this standard is journaled as at 16 a boom 17, which may be called a "power boom" while on the opposite side of the tracks near the crossing 14 is another standard 18 also similarly erected on a suitable foundation and carrying a boom 19 journaled in a similar manner, this boom being in the following referred to as the "passive boom".

Each boom consists of a long upwardly directed arm 20 and a short downwardly directed arm 21 both together forming a stiff structure. The two arms 20 and 21 are balanced around the axis of the journal 16, so that the boom, whether raised or lowered will not change its position of its own accord. The short arm 21 may for this purpose be loaded with weights 22 inserted therein.

At 23 on the long arm 20 is shown a lantern intended to give a visible signal at night.

The "power boom" 17 is provided with a spring 24 secured as at 25 to the short arm 21 and preferably coiled around the journal as seen in Fig. 2, its free end 26 extending in the direction of the long arm 20. A similarly constructed spring 27 is fastened to the long arm as at 28, coiled around the boom journal 16 and its free end 29 extending in the direction of the short arm 21. This latter spring 27 is the raising spring while the spring 24 is the felling or lowering spring of the boom 17. To the free end 26 of the lowering spring a link 30 is attached, the lower end of which connects with a two armed lever 31 fulcrumed as at 32 in a suitable bearing 48 on the stand 15. The short arm of the lever 31 has hinged connection as at 33 with a bell crank 34 fulcrumed as at 35 on a suitable bearing 36, which is rigidly secured on the foundation or ties of the track. This bell crank 34 has an upwardly extending ear 37, in which is fulcrumed a connecting rod 38, the other end of which being fulcrumed as at 39 in a horizontally swinging bell crank 40 adjacent to the rail 12 of track 10. By means of a long rod 41 the other arm of bell crank 40 connects

with the downwardly directed finger 42 of the treadle 43 having an upwardly projecting toe 44 with an arcuate top surface 45 normally standing above the top of rail 12. This treadle 43 is journaled as at 46 in the bracket 47 rigidly secured to rail 12 in such a manner, that the treadle 43 with its inner side lies along the head of the rail 12.

10 It will now be evident that, when a train approaches in the direction of arrow X on track 10, the car wheels 49 running on the rail 12 will depress the toe 44 of the treadle 43, thereby pulling on rod 41 swinging the bell crank lever 40 in the same direction and pulling connecting rod 38 in direction of arrow Z, causing a pulling downwardly on the free end 26 of the lowering spring through the intermediary of parts 34, 31 and 30. Before the approach of the train the booms are supposed to be raised and, being balanced, a slight downward pressure on the free end 26 of the lowering spring 24 will now cause the long arm 20 to be felled down across the street or road which crosses the tracks and in this manner close the crossing.

The other track 11 has similar connections between the elbow lever 34 and its treadle 43^a and parts 38^a, 39^a, 40^a, 41^a and 47^a all corresponding to the parts 38, 39, 40, 41 and 47 in the above described connection.

Accordingly when the booms are raised and a train approaches on track 11 in direction of arrow Y, the car wheels will depress the treadle 43^a and by means of the enumerated connection parts will also lower the "power boom" 17.

As best seen in Figs 1, 2 and 4 the two booms 17 and 19 are positively connected by means of a link 50 engaging with its upper end an aperture 51 behind the journal 16 that is in the short arm 21. The lower end of the link 50 engages a horizontal arm 52 of a bell crank 53 fulcrumed as at 54 in bearing 55 secured to the bottom of the standard 15. The "passive boom" 19 is similarly provided with a link 56 connected with the horizontal arm 57 of a bell crank 58 fulcrumed in a bearing 59 secured to the bottom of the standard 18. The downwardly directed arms of bell cranks 53 and 58 are connected by means of a rod 60 which runs all the way across both tracks 55 and preferably below the rails in order to have free movement in its length direction.

It will now be understood that directly the "power boom" 17 swings whether up or down, this movement is communicated through the parts 50, 53, 60, 58 and 56 from the "power boom" 17 to the "passive boom" 19. In this manner the "passive boom" will always follow the movements of the "power boom" 17.

65 The free end 29 of the raising spring 27

has a link 65 attached thereto, the lower end of which engages with the bar or lever 66, which corresponds to the double armed lever 31 already described and the other connecting parts 67, 68, 69, 70, 71 and 72 correspond in all respects with the already described parts 34, 38, 40, 41, 47, and 43 in the same order.

It will now be evident that a train entering from the left end of track 10 as seen in Fig. 1 and running in direction of arrow X will pass out at the other end of the track over the treadle 72 situated at that end and depress the treadle and through the intermediary of the connecting parts enumerated 75 actuate the link 65 and free end 29 of the spring 27 to pull on the latter and in this manner raise the boom into upright position. Similarly a train having entered from the right hand end of track 11 in Fig. 1 and running in direction of arrow Y will leave the track over the treadle 72^a situated at this end thereof and depress the same, whereupon the intermediary connecting parts 70^a, 69^a, 68^a all corresponding to the previously described parts, carrying the same numerals 80 will actuate the lever 66 and link 65 to pull down the end 29 of the raising spring 27.

The device as described above explains the simplest construction of the invention but it 95 is evident, that, for long connections and curved tracks it would be necessary to introduce anti-friction means to facilitate the action of the moving parts and the scope of the claims is intended to cover such modifications.

The proper distance between the railway crossing and the actuating treadle is about fifty feet or in other words the distance between the approaching treadle and the 105 leaving treadle would be about one hundred feet.

Having thus described the invention, what is claimed as new is:

1. A railway gate comprising a boom, a 110 standard therefor, a horizontal journal in said standard, said boom having a long arm and a short arm balanced substantially around the axis of the journal and means for swinging the boom in a vertical plane 115 actuated by a passing vehicle wheel, said means including treadles fulcrumed on a wheel track and having a toe normally projecting above the same, springs secured with one end to the long and short arms of said 120 boom respectively and the intermediary portion of each spring coiled around said journal and suitable connection between said treadle and said springs.

2. A railway gate comprising a boom, a 125 standard therefor, a horizontal journal in said standard, said boom having a long arm and a short arm balanced substantially around the axis of the journal and means for lowering and raising said boom ac- 130

5 tuated by a passing vehicle wheel; said lowering means including a treadle fulcrumed on a wheel track and having a toe projecting above the same, a spring having one end secured to the long arm of said boom adjacent said journal, its free end extending along the other arm of the boom and its intermediary portion coiled around said journal and a series of links and bell cranks connecting said treadle with said free end of the spring.

10 3. A railway gate comprising a boom, a standard therefor, a horizontal journal in said standard, said boom having a long arm and a short arm balanced substantially around the axis of the journal and means for lowering and raising said boom actuated by a passing vehicle wheel; said raising means including a treadle fulcrumed on a 15 wheel track and having a toe projecting above the same, a spring having one end secured to the short end of said boom adjacent said journal, its free end extending along the other arm of the boom, and its intermediary portion coiled around said journal, and a series of links and bell cranks connecting said treadle with said free end of the spring.

necting said treadle with said free end of the spring.

15 4. A railway gate comprising a boom and a standard therefor, a horizontal journal in said standard, said boom having a long arm and a short arm balanced substantially around the axis of the journal, means for lowering the boom and other means for raising the boom, said means being actuated by a passing vehicle wheel, said lowering means including a treadle fulcrumed on the wheel track, a spring having one end secured to said short arm and its intermediary portion coiled around said journal and a series 20 of links and bell cranks connecting said treadle with the free end of said spring; said raising means including a treadle fulcrumed on the wheel track, a spring having one end secured to said long arm and its intermediary portion coiled around said journal, and a series of links and bell cranks connecting said other treadle with the free 25 end of said other spring.

In testimony whereof I affix my signature.

CARL G. HUTH. [L.S.]
